TRESTLE OR SAW HORSE

Application filed July 6, 1929. Serial No. 376,424.

Our invention relates to an improvement in trestles or saw horses, and the object in general is to provide a foldable structure adapted to be shipped and transported in a compact form when folded, and to provide a rigid and stable trestle or saw horse when unfolded. Other objects are embodied in the foldable legs having hinged connections of novel form, in the simple and effective means for locking the folding legs against any possibility of collapsing when the trestle or saw horse is in use, and in the means for lowering or raising the main beam and permitting interchangeability of the parts, all substantially as herein shown and described.

In the accompanying drawings, Fig. 1 is a side elevation of the trestle or saw horse unfolded, and Fig. 2 is a similar view with the legs folded. Fig. 3 is a bottom view of the device when folded as shown in Fig. 2. Fig. 4 is a transverse section of the device unfolded, and Fig. 5 a similar view with the legs partly folded together. Fig. 6 is an enlarged sectional view of one end of the trestle, with the legs partly broken away, on line 6-6 of Fig. 4. Fig. 7 is a cross section of the device taken on line 7-7 of Fig. 6. Fig. 8 is a bottom view, partly in section, on line 8-8 of Fig. 6. Fig. 9 is a cross section on line 9-9 of Fig. 6. Fig. 10 is a cross section corresponding to Fig. 7, but showing the legs unfolded. Fig. 11 is a perspective view of one of the legs. Figs. 12 and 13 are side and sectional views, respectively, of a vertically adjustable attachment for supporting the main bar or beam of the trestle, and Fig. 14 is an end view of a substitute holder for the bar or beam.

The trestle or saw horse comprises a main bar or beam A and two pairs of foldable legs B-B pivotally hinged to metal brackets C-C which are secured by lag screws 2 to the flat bottom face of bar or beam A. The separate sets of legs and brackets are identical in construction, and therefore a description of one will serve for the other, including the designating characters therefor. Thus, each attachment bracket C consists of a flat metal plate having two depending loops or eyes 3-3 which are spaced apart and con-

tain circular openings having rounded or beveled inner edges 4. A transverse loop or keeper portion 5 is also cast integral with the plate or bracket C intermediate the ends thereof opposite the loops or eyes 3 where- 55 in a locking member D may be slidably and tiltably confined. The legs B are curved in different planes to provide substantial spreading distances between the legs and so that the legs may be inclined outwardly with 60 the sides of the beam and also inclined outwardly relatively to the ends of the beam, thereby providing stable end supports for the beam when the legs are completely unfolded. To permit each pair of legs to be 65 folded closely together, and also folded substantially parallel with the beam, as shown in Fig. 2, the legs are each provided with round tapering trunnions 6 which fit loosely within the open loops or eyes 3 and terminate 70 in rounded hinged extremities 7-7 connected together by a pivot pin 8 midway between the two loops or eyes 3-3, see Fig. 7.

The hinged extremities 7-7 have flat meeting faces on the medial line of the trunnions, and the trunnions are rounded and tapered where they extend through the loops or eyes 3-3. Thus, the trunnions are free to rock within the eyes to permit the legs to be folded and unfolded with pin 8 as the 75 axis of turning movement. When the legs are folded closely together, they may be jointly rotated and folded against the beam, the trunnions being free to rotate within the loops or eyes 3-3. However, the legs can 80 only swing towards the center of the beam during such folding movements, but when the legs are unfolded and placed in the vertical inclined position (shown in Fig. 1) definite stop relations are established between 85 the legs and bracket plate C.

Each leg is a casting having a flat side wall or extension 10 adapted to overlap and clamp the flat side wall of beam A, and each leg also includes an end wall or right-angled flange 95 11 extending inwardly beneath the beam and fore-shortened at its upper end to abut against plate C when the leg is fully extended or unfolded. This abutting or stop portion 12 on the leg is widened and extends towards 100

the slotted keeper portion 5 on bracket C to provide an overhanging lip on each leg having a bottom face 14, which is inclined outwardly and upwardly, see Figs. 9 and 11, to permit locking member D to interlock therewith. One end of locking member D is notched or curved to fit the beveled or inclined bottom faces of the lugs 12 on the legs, see Fig. 9, and the opposite end of locking member D carries a set screw 15 adapted to engage the bottom of bracket C, whereby the locking member may be tilted or rocked within its keeper 5 in clamping the parts together. In that event, the legs are rigidly secured to the bracket and the beam and cannot be folded or unfolded. Moreover, in applying a clamping pressure by set screw 15 the locking member presses upwardly against the lugs or loops 12 on the legs, thereby tending to swing the flat side extensions 10 of the legs against the flat sides of the beam.

Accordingly, the lower supporting ends of the legs will be spread apart and will be locked in that spreading relation. However, each pair of legs is further provided with a set of connecting links 16-16' near their lower ends to limit the spreading movement of the legs and to relieve the strain on the flat clamping extensions 10 when the legs are unfolded. An additional locking result is obtained by locking the links 16-16' when unfolded. Thus, an eccentric lever 17 is mounted rotatably upon one link 16' opposite the concaved end edge 18 of the other link 16, see Fig. 4.

When the legs are unfolded and the links are straightened, the eccentric 17 may be rotated into and out of locking position thereby preventing the links from buckling when locked together.

Preferably beam A is made of wood, and the inner clamping faces of the leg extensions 10 are provided with pointed spurs or projections 19 adapted to penetrate the wood, thus enhancing the clamping and bracing effect between the legs and the beam. However, in lieu of clamping beam A directly between the leg extensions 10, we may use a separate supporting member 20 having ratchet teeth 21 on opposite sides thereof, see Fig. 12. In this case the upper ends of the clamping extensions 10 are beveled to engage the ratchet teeth, and the beam supporting member 20 may be clamped and held at different elevations when the legs are unfolded or spread apart. The beam may either rest within a concaved seat 22 at the top of ratchet member 20, or it may be secured within a bifurcated holder 23 having a supporting stem 24 adapted to seat within a vertical socket 25 in ratchet member 20. A substitute holder 26 having diverging arms 27 may be used instead of holder 23, but in either case the bar or beam A of the trestle may be raised or lowered relatively to the foldable

legs B-B, and sufficient forms of bars or beams used therewith for different purposes.

What we claim, is:

1. A trestle or saw horse, comprising a beam, brackets affixed to opposite ends of the beam having depending loops, and separate pairs of foldable legs having trunnions pivotally connected to each other and rotatably confined within the loops of said brackets. 70

2. A trestle or saw horse, comprising a beam, brackets affixed to opposite ends of the beam having depending loops, separate pairs of foldable legs having trunnions pivotally connected to each other and rotatably confined within the loops of said brackets, and means for locking said legs rigidly to the beam when unfolded. 80

3. A trestle or saw horse, comprising a beam, brackets affixed to the beam having depending loops, foldable legs having tapered trunnions pivotally connected together and rotatably confined within said loops, and means supported upon said brackets for locking said legs when unfolded. 85

4. A trestle or saw horse, comprising a beam, brackets secured to said beam having depending portions provided with beveled openings, foldable legs having round tapered trunnions hinged together and rotatably confined within said beveled openings, and means for locking said legs rigidly when unfolded. 90

5. A trestle or saw horse, comprising a beam having brackets and foldable legs rotatably connected to said brackets, said legs having beveled projections thereon, and a locking member supported upon said brackets having clamping screws to effect interlocking between said brackets and said beveled projections. 100

6. A trestle or saw horse, comprising a beam having foldable legs formed with round tapered trunnions having perforated extremities and pivot pins connecting said extremities, and brackets to support said beam having depending loops adapted to rotatably confine said trunnions and to promote a rocking movement of the trunnions therein. 110

7. A trestle or saw horse, comprising a beam having legs pivoted thereto adapted to fold and unfold, including connecting links for said legs, and an eccentric for frictionally locking said links mounted upon one and cooperating with the other of said links. 115

8. A trestle or saw horse, comprising a beam, folding legs hinged together and rotatably connected to said beam, foldable connecting links for said legs, one of said links having a concaved edge, and a rotatable eccentric mounted on the other link opposite said edge. 120

9. A trestle or saw horse, comprising a beam, separate pairs of legs having clamping extensions for said beam and having their legs pivotally connected with each other, 125

brackets affixed to said beam having depending portions rotatably connected with said legs, stop lugs on said legs adapted to engage said brackets, and locking members mounted upon said brackets and engageable with said lugs.

10. A trestle or saw horse, comprising a beam, a bracket affixed to each end of said beam having depending loops, and a slotted keeper opposite said loops, legs having round tapered trunnions extending through said loops and pivotally connected at their meeting extremities, said legs having stop lugs engageable with said bracket and slideable, 15 tilttable locking members confined within said keeper and engageable with said lugs.

11. A trestle or saw horse, comprising a beam, ratchet devices for supporting said beam, and foldable legs pivotally connected 20 with each other adapted to clamp said ratchet devices therebetween.

12. A trestle or saw horse, comprising foldable legs pivotally connected with each other, a socket member adapted to be clamped by 25 and between said legs, and a beam supporting member removably seated within said socket member.

13. A trestle or saw horse, comprising a beam, forked holders for said beam, supporting members for said holders, and separate foldable legs pivotally connected with each 30 other adapted to clamp said members at different elevations therebetween.

In testimony whereof we affix our signatures.

WILLIAM C. RISBRIDGER.
